CLAIM

The ornamental design for a trolling motor mount, as shown and described.

DESCRIPTION

FIG. 1 is a top perspective view of a trolling motor mount in accordance with the present invention;

FIG. 2 is a left side view of the trolling motor mount of FIG. 1;

FIG. 3 is a right side view of the trolling motor mount of FIG. 1;

FIG. 4 is a bottom view of the trolling motor mount of FIG. 1;

FIG. 5 is a top view of the trolling motor mount of FIG. 1; FIG. 6 is a front view of the trolling motor mount of FIG. 1; FIG. 7 is a rear view of the trolling motor mount of FIG. 1; and,

FIG. 8 is a top perspective view of the trolling motor mount of FIG. 1 shown with a trolling motor head and a foot pedal. The dash-dot-dash broken lines illustrate the boundary of the claimed design and forms no part of the claim. The evenly dashed broken lines illustrate environmental structure and forms no part of the claimed design.

1 Claim, 8 Drawing Sheets
